WIRE STRAIGHTENER

Charles F. Campbell, Reno, Nev.
(538 I St., Sparks, Nev. 89431)

Filed Oct. 2, 1968, Ser. No. 13,814

Term of patent 14 years

Int. Cl. D8—02

U.S. Cl. D8—44

FIG. 1

FIG. 7

FIG. 2

FIG. 6

FIG. 3

FIG. 8

FIG. 5

FIG. 4

FIGURE 1 is an elevational view of one side of a wire straightener, showing my new design;

FIGURE 2 is a bottom plan view;

FIGURE 3 is an elevational view of the opposite side from that shown in FIGURE 1;

FIGURE 4 is a top plan view;

FIGURE 5 is an elevational view of one end;

FIGURE 6 is an elevational view of the opposite end from that shown in FIGURE 5;

FIGURE 7 is a sectional view, the plane of the section being indicated by the lines 7—7 in FIGURE 1; and

FIGURE 8 is a sectional view, the plane of the section being indicated by the line 8—8 in FIGURE 1.

I claim:

The ornamental design for a wire straightener, as shown and described.
